UNITED STATES PATENT OFFICE

CHARLES M. EVANS, OF SAPULPA, OKLAHOMA, ASSIGNOR TO BARTLETT-COLLINS COMPANY, OF SAPULPA, OKLAHOMA, A CORPORATION OF OKLAHOMA

DESIGN FOR A PITCHER

Application filed July 22, 1932. Serial No. 44,408. Term of patent 7 years.

To all whom it may concern:

Be it known that I, CHARLES M. EVANS, a citizen of the United States, residing at Sapulpa, Creek County, in the State of Oklahoma, have invented a new, original, and ornamental Design for Pitchers, of which the following is a specification, reference being had to the accompanying drawing, forming a part thereof, and in which the figure is a perspective view of a pitcher embodying my design.

The design includes a series of panels or

sections provided with protuberances of generally pyramidal or conical configuration varying to some extent as to distinctness and general contour with variations in the shape of the pitcher.

I claim:

The ornamental design for a pitcher, substantially as shown and described.

In testimony whereof I have hereunto set my hand.

CHARLES M. EVANS,
